FASTENING DEVICE FOR BUBBLE CAP ASSEMBLIES

James P. Dunn, Springfield, Mass., assignor to
 Gilbert & Barker Manufacturing Company,
 West Springfield, Mass., a corporation of Mass-
 achusetts

Application January 4, 1952, Serial No. 264,898

2 Claims. (Cl. 261—114)

1

This invention relates to an improved fastening device for holding the parts of a bubble cap assembly together and to a floor plate of a bubble tray of a fractionating tower or the like.

The invention has for an object an improved form of wedging device for coaction with the top wall of the bubble cap and the upper end of the hold down member of a strong back to hold the cap in place on the floor plate of the bubble tray.

More particularly, the invention provides a fastening device of this character, wherein the two opposed surfaces of the wedge are formed on separate members which are interconnected together at one end only, thereby enabling adjustment of the slope of the wedge by bending one of the two members and also enabling a certain amount of spring action between the two surfaces of the wedge that tends to retain the members in position.

The invention also has for an object the provision of a wedging device, which includes one member of cylindrical form, capable of coaction with a drilled hole in the hold down member, in place of the usual rectangular slot necessary for a wedge of ordinary form, the construction being especially suitable where the hold down members have considerable thickness, such that slots cannot be readily and inexpensively formed as by punching.

The invention will be disclosed with reference to the illustrative embodiment of it in the accompanying drawings, in which:

Fig. 1 is a top plan view of a bubble cap assembly held together by the fastening device of this invention;

Figs. 2 and 3 are sectional elevational views taken on the lines 2—2 and 3—3, respectively, of Fig. 1;

Fig. 4 is a fragmentary sectional view taken similarly to Fig. 3 showing a modification of the fastening device; and

Fig. 5 is a view taken similarly to Fig. 2 showing the application of the invention to a different form of bubble cap.

Referring to these drawings, a portion of a floor plate of a bubble tray is shown at 1, and such plate (Fig. 2) has a circular opening therethrough in which a chimney 2 or riser is engaged. The chimney has an outturned base flange 3, which abuts the lower face of plate 1, when the chimney is thrust upwardly through the tray opening as far as possible. The chimney preferably tightly fits the tray opening so as to be frictionally retained in position without

5 manual assistance during the assembly of the other parts of the bubble cap assembly. A cross bar 4, or so-called strong back, diametrically spans the lower portion of the chimney 2 and has centrally fixed thereto a hold down member 5 in the form of an unthreaded bolt 5, which extends upwardly through the chimney and above the upper end of the same. This cross bar is notched at its upper and outer corners, forming 10 shoulders 6, which engage the base flange 3 at two diametrically opposite points, and an upper portion 7, which is located between the notches and frictionally fits the chimney so that the strong back and its upstanding hold down member 5 may be retained in position without manual 15 assistance during the assembly of the bell cap 8. The latter has a central hole in its top wall to receive the upper end of member 5. The lower end of the cylindrical portion of cap 8 rests upon the upper face of plate 1 and the parts are held together by the wedging device of this invention which acts to pull member 5 upwardly and press cap 8 downwardly in a manner to be later described in detail. The cylindrical portion of the cap encompasses the chimney 2 in spaced coaxial relation and has the usual slots 9 to permit the outflow of the gases. The gases rise through the chimney, pass down in the space between the cap and chimney, out through slots 9 and bubble up through liquid, which is maintained on the tray at a predetermined level above the upper ends of slots 9.

20 The bubble cap assembly, as thus far described, is of well known form. The details are not essential to the present invention and they may be varied in many ways as desired, because the invention is primarily concerned with a special form of wedging device acting on the top of the cap and the upper end of a hold down bolt to force them apart.

25 This wedging device is characterized in that the two effective wedging surfaces of the device are provided on the outer and non-adjacent surfaces of two separate members, which are connected at one end to a suitable support and project cantilever fashion, one above the other from the support. Conveniently, one such member is a cylindrical pin 10 (Fig. 3), the support is the upstanding leg 11 of an angle iron and the other member is the horizontal leg 12 of the angle iron. The wedging surfaces of these members are adapted to engage the top wall of the cap 8 and the hold down member to exert an upward force on the member and a downward force on the cap. Broadly, this may be done in

any suitable way. However, a simple and desirable way is that wherein the upper member is a cylindrical pin and is engaged in a hole which is drilled through the hold down member 5 at an acute angle to the plane of the top wall of the cap 8 and the other member is flat and rests on the top wall of the cap and has a notch, such as 13 (Fig. 1), in one end to form a fork with arms 14 which straddle the hold down member. The pin 10 may be supported from the angle iron leg 11 in any suitable way. In Fig. 3 the pin extends through a hole drilled in leg 11 and its outer end is welded to the leg, as indicated at 15. In Fig. 4, a corresponding pin 10' has one end slidably mounted in a hole in the leg 11.

In use, the forward end of the pin 10 is inserted in the hole in member 5 and then driven toward the right, as viewed in Fig. 3 or 4. This will cause the pin 10 to raise member 5 and the leg 12 of the angle iron with its legs 14 to press downwardly on cap 8, forcing the lower end thereof against the upper face of plate 1 while the upward pull on member 5 will force the shoulders 6 of the strong back 4 against the base flange 3 of the chimney, thereby forcing such flange against the lower face of plate 1. In the Fig. 3 form, the pin and angle iron may be moved together by a hammer blow on leg 11 while in the Fig. 4 form, these two parts may be moved the one independently of the other.

The invention may also be used with bubble cap assemblies, such as shown in Fig. 5, wherein the chimney 16 has a base flange 17, which rests on top of plate 1, and the cap 18 has a series of vanes 19, fixed thereto and resting on the upper end of the chimney. Here, the cap 18 is supported from the upper face of plate 1 but through the intermediary of the chimney and not directly as before. Each vane is notched to provide a shoulder 20 to rest on the upper end of the chimney and a shoulder 21 to abut the outer periphery of the chimney, whereby the cap and chimney are held in proper spaced coaxial relation. The lower end of cap 18 does not touch plate 1 and has a circular series of annularly spaced notches 22, serving the same purpose as the slots 9 of Figs. 1 to 3. The strong back 4, constructed as before, has its upper portion 7 extending through the hole in plate 1 and into the lower end of the chimney 16, whereby to align the latter with the hole. The shoulders 6 then engage the lower face of plate 1. The hold down member 5 extends upwardly as before, through the chimney 16 and cap 18 and the wedging device is applied, as before, to force the member 5 upwardly and cap 18 downwardly, whereby to clamp the cap against the chimney and the latter against plate 1 and the shoulders 6 of the strong back against the lower face of plate 1.

The particular form of strong back, herein shown, is constructed from two strips 23, suitably secured together in face to face relation, as by two spot welds, indicated at 24. The central portion of each strip 23 is bent into semi-cylindrical form as at 25 and these two portions encircle the shank of bolt 5. Below these portions 25 the strips are slotted to receive the head 26 of the bolt and prevent the same from turning.

The invention provides a wedging device of simple and inexpensive form. It has been common to use a wedge which is of rectangular cross

section and relatively high and narrow, engaging it in an elongated slot in a flat and relatively thin hold down member, which extends through a slot in the bubble cap. In such cases, the slot in the hold down member can be formed by punching out the thin sheet metal. However, where the hold down member is cylindrical, as herein shown, or otherwise of substantial thickness, it is relatively expensive to form the slot and the present invention offers a much cheaper, simpler and better solution of the problem. The angle iron may be struck up from sheet metal and the pin cut from heavy wire stock and welded in place. The member 5 simply needs to have a hole drilled therein. The pin can be readily bent with a hammer blow to vary its inclination, where necessary for proper engagement of the parts. The construction, in effect, has the two effective surfaces of the wedge in spaced relation and supported at one end only so that there is a certain amount of spring action between them that enables the wedging device to be held in place without the bending of the ends of the wedge as is necessary where the wedge is of the ordinary form, as above described. The device is easily installed and as easily removed, simply with a hammer blow on one end or the other of the wedging pin.

The invention thus provides an improved form 30 of wedging device for fastening the parts of a bubble cap assembly together and to a floor plate of a bubble tray of a fractionating tower.

What is claimed is:

1. In a bubble cap assembly, having a floor 35 plate with an opening therethrough, a bell cap supported from the upper face of said plate, a strong back bridging said opening and having its ends engaged beneath said plate, and a hold down member fixed at one end to the strong back 40 and extending upwardly through the top wall of said bell cap; a wedging device engaging the top wall of the cap and a portion of said hold down member at a location above said cap for exerting a downward force on the cap and an upward force on said member, said device comprising a support 45 resting on top of the cap and upstanding therefrom and two members connected at one end to the support and projecting one above the other in cantilever fashion from the support, the outer 50 and nonadjacent surfaces of said members converging and constituting the effective wedging surfaces of the device, said hold down member at a location above the top wall of the cap having a cylindrical hole therethrough, the axis of which is inclined to the plane of said wall, the upper member of said wedging device consisting of a cylindrical pin engaged in said hole.

2. A bubble cap assembly, as claimed in claim 1, in which the upper member of the wedging device is slidably mounted in the support.

JAMES P. DUNN.
